By *Chandler Chandler* Attorneys

UNITED STATES PATENT OFFICE.

HARRY W. OSBRINK, OF RIVERSIDE, CALIFORNIA.

DESIGN FOR A FIGURE TOY.

54,280.

Specification for Design.

Patented Dec. 9, 1919.

Application filed May 3, 1919. Serial No. 294,592. Term of patent 7 years.

To all whom it may concern:

Be it known that I, HARRY W. OSBRINK, a citizen of the United States, residing at Riverside, in the county of Riverside and State of California, have invented a new, original, and ornamental Design for Figure Toys, of which the following is a specification, reference being had to the accompanying drawing, forming a part thereof.

In said drawing, Figure 1 is a perspective view of the toy of my design.

Fig. 2 is a rear elevation, and

Fig. 3 a front elevation.

I claim:

The ornamental design for a figure toy, as shown.

HARRY W. OSBRINK.
